UNITED STATES PATENT OFFICE.

SETH H. SMITH, OF NORTH ADAMS, MICHIGAN, ASSIGNOR OF ONE-HALF
HIS RIGHT TO W. H. WILLBER, OF SAME PLACE.

IMPROVEMENT IN EGG-CARRIERS.

Specification forming part of Letters' Patent No. **139,431**, dated May 27, 1873; application filed
March 12, 1873.

To all whom it may concern:

Be it known that I, SETH H. SMITH, of North Adams, in the county of Hillsdale and in the State of Michigan, have invented certain new and useful Improvements in Egg-Carrier; and do hereby declare that the following is a full, clear, and exact description thereof, reference being had to the accompanying drawings and to the letters of reference marked thereon, making a part of this specification.

The nature of my invention consists in the construction and arrangement of an egg-carrier, as will be hereinafter more fully set forth.

In order to enable others skilled in the art to which my invention appertains to make and use the same, I will now proceed to describe its construction and operation, referring to the annexed drawing, in which—

Figure 1 is a perspective view with the box broken open to show the interior of the egg-carrier; and Fig. 2 shows the pieces of which the pockets are formed.

A represents a box of any suitable dimensions and construction, in which are formed horizontal series of pockets for the eggs. Each series is formed of a suitable number of straight pieces, B B, and two folded pieces, c c, of paper or other similar suitable material. Each piece B is cut from both edges inward with slots b b, which alternate as shown in

Fig. 2, and extend inward about one-third the width of the piece.

The pieces c c are folded and then cut partially through every fold with slots corresponding to the number of pieces B to be used. One piece, C, is then placed in the slots on the pieces B from one side and another piece from the other side the cut folds, meeting alternately as shown in Fig. 1 and forming double pockets, but only half the depth required; the eggs projecting above one series being covered by the lower half pockets of the series above. It will be seen that the eggs can be picked out one by one if so desired.

Having thus fully described my invention, what I claim as new, and desire to secure by Letters Patent, is—

The combination of the flat strips B B with notches b b, alternating on both edges as shown, and the bent strips C C cut and fitting into said notches, as shown, and forming half-pockets, all substantially as set forth.

In testimony that I claim the foregoing I have hereunto set my hand this 5th day of February, 1873.

SETH H. SMITH.
